UNITED STATES PATENT OFFICE.

ROBERT H. OWEN, OF BUTTE, MONTANA, ASSIGNOR OF ONE-THIRD TO E. F. MAGINN
AND ONE-THIRD TO M. H. GLEASON, BOTH OF BUTTE, MONTANA.

GRAIN CLEANER.

Application filed September 10, 1919. Serial No. 322,796.

To all whom it may concern:

Be it known that I, ROBERT H. OWEN, a citizen of the United States, residing at Butte, in the county of Silver Bow and State 5 of Montana, have invented new and useful Improvements in Grain Cleaners, of which the following is a specification.

This invention relates to improvements in grain cleaners.

10 The object of the invention is to provide a grain cleaner consisting in a receptacle or housing and so arranged that upon grain being delivered into said housing under air pressure, that the air pressure employed for 15 delivering said grain, may be utilized for subjecting the grain to a cleaning process.

Other objects, and objects relating to details of construction, combination and arrangement of parts will hereinafter appear 20 in the detailed description to follow.

The invention is illustrated by way of example in the accompanying drawings, in which:—

Figure 1 is a longitudinal sectional view 25 taken through the grain cleaner.

Figure 2 is a transverse sectional view taken substantially on the lines 2—2 of Figure 1.

Figure 3 is a top plan view of the receptacle or housing.

Figure 4 is a perspective view of a slide or valve employed in connection with the receptacle or housing.

Referring to the drawings more particularly, in Figure 1, 60 indicates generally a fan housing or casing into which grain may be delivered. Within this housing there is positioned a shaft 59 supporting the fan blades 61, and this fan may be employed 40 for forcing grain through a conduit 64 which communicates through the opening 63 with a receptacle 62. The receptacle 62 is preferably of the shape shown, and within the receptacle there is arranged a pair 45 of division walls 62' and 63'. The division wall 62' at its upper end engages with the upper end portion of the division wall 63', while its lower end is provided with an offset portion 61' which is adapted to form a 50 restricted passage 67 through which the grain deposited in the receptacle through the conduit 64 will pass. The division wall 63' is adapted to establish a separate passage 64 which communicates at its upper 55 end with the upper end portion of the re-

ceptacle 62 and its lower end substantially in alignment with a transverse passage 66 provided in the one side of a discharge chute 65.

The upper end wall of the receptacle 62 is provided with a plurality of openings 68 and over which there is positioned a plate member 69. The plate member 69 is slidably held by the means of a pair of angle members 70 and is adapted to be moved 65 with relation to the opening 68 to regulate the passage of air under atmospheric pressure into the receptacle 62.

The present cleaning arrangement may be incorporated with a thrashing machine or 70 with other suitable means whereby grain may be delivered into the receptacle 62. The grain may be delivered to this receptacle with foreign particles therein. The grain will gravitate through the opening 67 75 and from thence pass into the chute 65. The air pressure used for delivering the grain into the receptacle 62 will pass through the passage 64 and from thence through the transverse passage 66. It is apparent therefore as the grain leaves the receptacle 62 and passes into the chute 65 it will be subjected to a transverse current 80 of air from the passage 64 and thereby clean the same of foreign particles which may be 85 removed by a blast of air.

The strength of the current of air passing transversely of the grain may be regulated through manipulation of the valve member or plate 69. 90

Having thus described my invention, I claim:—

1. In a device of the character described, a grain cleaner comprising a receptacle 95 communicating at its lower end with a discharge passage, and also having communicating therewith a conduit through which grain may be discharged into said receptacle under air pressure, a division wall within the receptacle adapted to form a restricted passage through which the grain entering the receptacle must pass before proceeding into the discharge passage, and a second division wall within the receptacle 100 adapted to form a channel whereby to cause the air entering with the grain to be directed against the grain after passing through said restricted passage in the receptacle.

2. In a device of the character described, 110

- a grain cleaner comprising a receptacle communicating at its lower end with a discharge passage, and also having communicating therewith a conduit through which grain 5 may be discharged into said receptacle under air pressure, a division wall within the receptacle adapted to form a restricted passage through which the grain entering the receptacle must pass before proceeding into 10 the discharge passage, a second division wall within the receptacle adapted to form a channel whereby to cause the air entering with the grain to be directed against the grain after passing through said restricted 15 passage in the receptacle, and a valve regulated vent in the top of the receptacle whereby to regulate the velocity of the air directed against said grain.
3. In a device of the character described, 20 a grain cleaner comprising a receptacle communicating at its lower end with a discharge passage, a division wall within the receptacle adapted to form a compartment into which grain may be discharged under 25 air pressure and also adapted to form a restricted passage or outlet at the lower end of said compartment through which the grain discharged in said compartment may pass, and means whereby the air under pressure resulting from the delivery of the grain 30 to said compartments may be delivered to transversely pass through the grain after the grain has passed through said restricted 35 passage.
4. In a device of the character described, a grain cleaner comprising a receptacle communicating at its lower end with a discharge passage, a division wall within the receptacle adapted to form a compartment in 40 which grain may be discharged under air pressure and also adapted to form a restricted passage or outlet at the lower end of said compartment through which the grain discharged in said compartment may pass,

means whereby the air pressure resulting 45 from the delivery of the grain to said compartments may be delivered to transversely pass through the grain after passing through said restricted passage, and controlling means and an outlet in the receptacle adapted 50 to establish communication with the compartment to which the grain is delivered and the atmosphere.

5. In combination, a receptacle having a 55 division wall therein adapted to form a compartment, said compartment having an outlet through which grain to be separated may be delivered, a grain delivery conduit communicating with said opening, means whereby air pressure may be introduced into said 60 conduit for blowing grain into said compartment of the receptacle, said compartment having a restricted outlet at the lower end thereof through which the grain may 65 pass, and means whereby the air discharged in the compartment when delivering the grain thereto may be utilized for subjecting the grain to a transverse current of air to clean the same after its passage through 70 said restricted opening.

6. A grain separator, comprising a receptacle having a discharge opening, means whereby grain may be delivered to said receptacle under air pressure, and means whereby the air pressure for delivering said 75 grain may be utilized for subjecting the grain delivered to a cleaning process.

7. A grain separator, comprising a receptacle having a discharge opening, means whereby grain may be delivered to said receptacle under air pressure, and means whereby the air pressure for delivering the said grain to the receptacle may be utilized for subjecting the grain discharged therefrom to a transverse current of air for cleaning said grain.

ROBERT H. OWEN.
